DESIGN FOR A RIBBON OR A SIMILAR ARTICLE

Charles Weiner, Chicago, Ill., assignor to Chicago Printed String Co., Chicago, Ill., a corporation of Illinois

Application March 20, 1933, Serial No. 47,530

Term of patent 7 years

To all whom it may concern:

Be it known that I, CHARLES WEINER, a citizen of the United States, and a resident of the city of Chicago, county of Cook, and State of Illinois, have invented a new, original, and ornamental Design for a Ribbon or a Similar Article, of which the following is a specification, reference being had to the accompanying drawing forming a part thereof.

On the drawing:

or similar article embodying my invention, with longitudinal lines indicating stripes of contrasting shades of two colors, and horizontal shade lines indicating an effect caused by the corrugation of the ribbon.

I claim:

The ornamental design for a ribbon or a similar article as shown and described.

CHARLES WEINER.
